DESIGN FOR A SUPPORTING RACK FOR KITCHEN UTENSILS, OR THE LIKE

William J. Marcus, Cleveland Heights, Ohio

Application December 14, 1937, Serial No. 73,614

Term of patent 3½ years

To all whom it may concern:

Be it known that I, William J. Marcus, a citizen of Germany, residing at Cleveland Heights, in the county of Cuyahoga and State of Ohio, have invented a new, original, and ornamental Design for a Supporting Rack for Kitchen Utensils, or the Like, of which the following is a specification, reference being had to the accompanying drawing, forming a part thereof, in which:

I claim:

The ornamental design for a supporting rack for kitchen utensils, or the like, as shown.

WILLIAM J. MARCUS.
